UNITED STATES PATENT OFFICE.

GEORGE PIERCE NABORS, OF ARGENTA, ARKANSAS.

COMBINED GRINDER AND GUMMER MACHINE.

1,347,965.

Specification of Letters Patent. Patented July 27, 1920.

Application filed June 8, 1918. Serial No. 239,070.

To all whom it may concern:

Be it known that I, GEORGE PIERCE NABORS, a citizen of the United States, residing at Argenta, in the county of Pulaski and State of Arkansas, have invented certain new and useful Improvements in Combined Grinder and Gummer Machines; and I do hereby declare the following to be a full, clear, and exact description of the invention, such as will enable others skilled in the art to which it appertains to make and use the same.

This invention relates to machines for grinding and gumming saws of gins or linters and the primary object of the invention is to provide a machine, which will accommodate a plurality of saws, whereby the same can be simultaneously ground and gummed.

Another object of the invention is to provide a grinder and gummer machine having improved means for operating the saws and gummer frame, so that the gummers will be brought into and out of contact with each saw tooth of the saws.

A further object of the invention is to provide a grinding and gummer machine having an improved means for adjusting the spindle carrying the saws, whereby the saws can be brought into and out of operative position in relation to the grinders and gummers.

A still further object of the invention is to provide an improved gummer and grinder having automatic means for stopping the grinder and gummers after the saws have been treated.

A still further object of the invention is to provide an improved grinding and gummer machine of the above character, which is efficient and durable in construction, one that is simple and easy to manufacture, and one that can be placed upon the market at a reasonable cost.

With these and other objects in view the invention consists in the novel construction, arrangement and formation of parts, as will be hereinafter more specifically described, claimed and illustrated in the accompanying drawings, forming a part thereof in which:

Figure 1 is a front elevation of the improved machine,

Fig. 2 is a horizontal longitudinal section

taken through the improved machine directly above the grinders, 55

Fig. 3 is a transverse section taken on the line 3—3 of Fig. 1,

Fig. 4 is a transverse section taken on the line 4—4 of Fig. 2, 60

Fig. 5 is a detail transverse section taken on the line 5—5 of Fig. 1,

Fig. 6 is a fragmentary detail horizontal section taken on the line 6—6 of Fig. 5,

Fig. 7 is a detail view of the modified 65 form of grinding cylinder.

Referring to the drawings in detail, wherein similar reference characters designate corresponding parts throughout the several views, the numeral 1 generally indicates the improved machine, which includes the frame 2 in which is supported the grinding mechanism 3 and the gummer mechanism 4.

The frame 2 consists of the upright standards 5, 6, 7, 8, 9 and 10, which are arranged in pairs and connected at their lower ends by transverse beams 11, which form supporting feet for the frame. The upper ends of the standards 5, 6, 7, and 8 are connected by 75 transverse beams 12 and all of the beams are connected by longitudinally extending strips or braces 13. The standard 9 ends short of the other beams and is connected to the opposite beam 10 by a transverse beam 14 80 which is in alignment with transverse beams 15 which extend across the frame and are connected to the standards 5, 6, 7 and 8 and these beams are arranged intermediate the beams 11 and 12. The beam 14 is connected with the opposite beam 15 by relatively short braces 16, which form a rigid connection between the same. A relatively short upright 17 is secured to the beam 14 and is connected at its upper end to the 85 beam 8 by a beam 18. The uprights 5 and 7 are connected intermediate their ends by longitudinally extending beams 19.

The saw grinding mechanism 3 includes a shaft 20, which is journaled in a pair of 100 bearings 21 secured to the transverse beams 15. Keyed to the shaft 20 are a plurality of pairs of spaced grinding wheels 22, which may be formed of any suitable abrasive material. The grinding wheels 22 are spaced 105 so as to accommodate the width of a saw, so that both sides of the saw will be ground. It is to be understood that there are as many

pairs of grinding wheels as there are saws. The pairs of grinding wheels 22 are held in spaced relation by means of spacing washers or collars 23. If so desired a cylinder of abrasive material 22^a having a plurality of grooves 23^a for receiving saws may be substituted for the grinding wheels. One end of the shaft 20 is extended beyond the frame and has secured thereto a drive pulley 24 and an idle pulley 25, which are adapted to be engaged by a driving belt 26, which is adapted to engage either a live pulley 27 or an idle pulley 27^a mounted on the drive shaft 28, which is journaled in bearings 29 secured to the rear beams 6, 8 and 10. The drive shaft 28 is adapted to be driven from any suitable power source by means of a belt 30, which is trained around a drive pulley 31 and is adapted to be shifted to an idle pulley 32 secured to the shaft.

Pairs of spaced arms 33 are secured to the front face of the beams 5 and 7 and form brackets and supporting the bearings 34 and a saw mandrel 35. A plurality of circular saws 36 are secured to the mandrel 35 and are held in spaced relation to each other by means of spacing collars 37. The saw mandrel is positioned directly in front of the grinding mechanism and the bearings 34 are arranged to be shifted laterally of the frame, so as to bring the saws into engagement with the grinding wheel.

Each of the bearings 34 includes a lower block 38, which has a reduced portion 39 that is slidably mounted in a sliding plate 40 which has a pair of upstanding arms 41 which receive the depending portion. The reduced portion 39 is provided with a depending lug 42 which is loosely received between the arms 41, so that the same can readily slide in between the arms. The plate 40 has depending lug 43, which is slidably received between the arms 33. The arms 33 have their forward faces inclined downwardly and the upper ends of the same are connected by a front wall 44 and the rear faces of the arms are connected by a rear wall 45 which forms means for securing the arms to the standards 5 and 7. Shaft 46 extends in between the spaced arms 33 and are rotatably carried by the front walls 44 and are held against longitudinal and lateral movement by means of collars 47 which engage the front and rear faces of the front wall. The shafts 46 are provided with operating handles 48 and the bodies of the shafts are provided with threads 49 which extend through a threaded bore 50 formed in each of the depending lugs 43. The inner end of each shaft 46 is provided with a beveled gear 51 which meshes with a beveled gear 52 carried by each terminal of the longitudinally extending shaft 53 which is rotatably carried by the inner arms 33 and extends from the arms carried by one

standard to the arms carried by the other standard. Thus it will be seen that when one of the shafts 46 is rotated by means of the handles 48, the other will be rotated therewith and the bearing 38 through the medium of the depending lugs 43 traveling on the threaded portions 49 of the shafts 46 will be brought into and out of engagement with the saws according to the direction of the rotation of the shafts. The bearings can also be shifted longitudinally of the frame, by means of a longitudinally extending shaft 54 which has its ends provided with threads 55, which are extended through threaded bores 56 of the lugs 42. Thus it will be seen by suitable rotation of the shaft 54 the lugs 42 will be shifted between the arms 41 toward or away from each other carrying the bearings 34 therewith. The bearings 34 are provided with a detachable upper section 57 which provides means whereby the saw mandrel 35 can be readily removed from the bearings.

The gummer mechanism 4 includes swinging frame 58, which is mounted between the standards 5 and 7 and is swingably mounted on a shaft 59, which extends longitudinally of the frame and is rotatably mounted in a pair of bearings 60, which are carried by the upper ends of the standards 5 and 7. The frame 58 is provided with a plurality of upstanding bearings 61 which rotatably receive the shaft 59. A plurality of spaced beveled gears 62 are keyed to the shaft 59, and mesh with the beveled gears 63 keyed to the upper ends of the shafts 64 which carry the gummers 65. The shafts 64 extend vertically through the swinging frame 58 and are mounted in suitable bearings 66 which are held in place by set screws 67 which extend into the frame 58 and fit into annular grooves 68 formed in the bearings. The frame 58 is mounted for swinging movement, so that the gummers 65 may be brought into and out of engagement with the teeth of the saws, as the saw mandrel is rotated, by means which will hereinafter more fully appear. The frame is actuated by arms 69 which are pivotally connected as at 70 to the lower end of the frame 58 and the rear ends of the arms are provided with circular straps 71 which surround cams or eccentrics 72 that are keyed to a shaft 73, which extends longitudinally of the frame and is rotatably mounted in suitable bearings 74 and is positioned above the drive shaft 28. The shaft 73 is connected to the shaft 28 by means of a sprocket chain 75, which is trained around the sprocket wheels 76 which are keyed to the shafts 73 and 28. Thus it will be seen upon rotation of the shaft 28 the frame 58 will be swung back and forth through the medium of the eccentrics 72, the arms 69 and the shaft 73.

The saws are rotated step by step so that

as the frame 58 is swung back and forth, the gummers will engage a different tooth of the saws. This is accomplished by means of a ratchet wheel 77, which is detachably held in position on the inner end of the mandrel by means of a nut that is turned on a threaded end 79 of the mandrel. The ratchet wheel 77 is engaged by a dog 80, which is secured as at 81 to an arm 82, which 10 carries a circular strap 83, which is positioned around the eccentric cam 84, which is keyed to the shaft 73.

It will be seen that the eccentrics 84 and 72 are rotated by the shaft 73 and when the 15 dog 80 advances the saws one tooth, the frame 58 will be swung on the bearings 61 and the gummers 65 will be brought into engagement with a different tooth of the saws.

20 A longitudinally extending strip 85 is carried by the longitudinally extending beam 19, and carries a plurality of pairs of spaced arms 86, which have the upper ends thereof curved arcuately as at 87 and are 25 positioned directly in front of the pairs of grinder wheels 22. The outer edges of the pairs of arms 86 are beveled inwardly as at 88 and the same form means for guiding the saws into engagement with the grinder 30 wheels.

The shaft 59 has one end extended beyond the frame and keyed thereto is a pulley 89, which is operatively connected to a pulley 90 keyed to the drive shaft 28 by 35 means of a belt 91. Thus it will be seen that the gummers 65 are rotated, as the same are brought into and out of engagement with the saws.

A sliding rod 92 is mounted in suitable 40 guides 93 carried by the lower surfaces of the transverse beams 16 and the outer end of the rod is provided with upstanding arms 94, which engage the upper run of the belt 26 and form means for shifting the belt 45 from the drive pulley 24 to the idle pulley 25. A contractile spring 95 is coiled around the rod and one end of the same bears against one of the guides 93 and the other against a pin 96 carried by the rod. This 50 spring normally tends to slide the rod 92 outwardly and shift the belt 26 to the idle pulley. The inner end of the rod is provided with a hook 97, which engages the hook end 98 of a sliding rod 99, which is 55 mounted in suitable guides and carried by the beam 14. The rod 19 is pivotally connected by means of a pin 100, to a pivoted operating lever 101 which is provided with a slot 102 for receiving the pin. The lever 60 is pivoted intermediate its ends by means of a pivot pin 103 to the relatively short beam 16 and the outer end of the same is arranged to engage the shoulder 104 formed on the arm 105. Thus it will be seen that 65 the sliding rod 92 is held against the ten-

sion of the coil spring 95 by means of the rod 99, and the pivoted lever 101 and the arm 105. An expansion spring 106 is coiled around the rod 99 and is confined between the operating lever 101 and the beam 14, and the rod 99 is held against movement under the influence of the spring 106 by means of the operating lever 101 engaging the shoulder 104. A sliding rod 107 is mounted in guides 108 and 109 carried respectively by 70 the lower surface of the beam 16 and one of the beams 15. The inner end of the rod abuts the inner end of the sliding rod 92 adjacent to the hook end thereof and the outer end of the rod is positioned in the path of 80 an arm 110 having the anti-friction roller 111 mounted thereon. When the saws have made a complete revolution the arm 110 will come in contact with the outer end of the sliding rod 107 and push the same rearwardly, which in turn will engage the inner 85 end of the rod 92 and force the hooked end thereof out of engagement with the hooked end 98 of the rod 99 and allow the sliding rod 92 under the tension of the coil spring 90 95 to slide outwardly and thus shift the belt 26 to the idle pulley 27 and thus prevent further rotation of the grinders 22. The standards 6 and 8 are provided with grooves 112 so as to allow the rod 92 to slide laterally 95 when the rod 107 engages the same. An arm 113 is carried by the opposite face of the ratchet wheel 77 and is arranged to engage the outer end of the pivoted lever 101 which will lift the lever out of engagement with 100 the shoulder 104 of the arm 105 and thus allow the lever to swing on the pivot 103 under the influence of the coil spring 106 and shift the drive belt 30 to the idle pulley 32. The inner end of the lever 101 is provided with upstanding arms 114 which engage the drive belt 30 so that the same will be shifted upon movement of the lever.

In operation of the improved device the saw mandrel 35 carrying the desired number of saws is positioned in the bearings 34 and the same are then adjusted laterally of the machine as described above, to bring the saws into engagement with the grinding wheels 22. The machine is then started 110 and the grinding wheels are rotated which grind both sides of the saws, and the gummers 65 will be brought into engagement with each tooth of the saws by means of the ratchet wheel 77. When the saws have 115 made a complete revolution the grinders will be thrown out of operation through the medium of the belt shifting mechanism 107; and when the teeth of the saws then being engaged by the grinding wheels are 120 brought into engagement with the gummers by means of the ratchet wheel, the arm 113 will engage the lever 101 and detach the same from the shoulder 104, and the lever will shift the drive belt 30 out to the idle 125 130

pulley and thus stop rotation of the gummers.

In practice, I have found that the form 5 of my invention illustrated in the accompanying drawings and referred to in the above description, as the preferred embodiments, is the most efficient and practical; yet realizing the conditions concurrent with the adoption of my device will necessarily 10 vary, I desire to emphasize the fact that various minor changes in details of construction, proportion and arrangement of parts may be resorted to within the scope of the intended claims, when required, without 15 sacrificing any of the advantages of my invention as set forth.

What I claim as new is:

1. In a gumming and grinding machine, a saw mandrel support, a mandrel mounted 20 in the support, a plurality of saws carried by the mandrel, grinding means positioned in the rear of the mandrel, gumming means positioned above the mandrels, means for operating the grinding and gumming means, 25 and means for moving the mandrel support, so as to bring the saws into and out of engagement with the grinding and gumming means.

2. In a grinding and gumming machine, 30 a frame, grinding means rotatably carried by the frame, brackets carried by the frame and arranged in front of the grinding means, bearings slidably mounted in the brackets, a saw mandrel carried by the bearings, a plurality of saws carried by the mandrel, and means for operating the bearings, to bring the saws into and out of engagement with the grinding and gumming mechanism.

3. In a gumming and grinding machine, 40 a frame, a rotary shaft carried by the frame, grinding means mounted on the shaft, bearings adjustably carried by the frame, a saw mandrel mounted in the bearings, a plurality of saws mounted on the mandrel, means for adjusting the bearings for bringing the saws out of engagement with the grinding means, and a plurality of rotary operating gummers carried by the frame.

4. A gumming and grinding machine including a frame, a shaft carried by the frame, a plurality of grinding wheels mounted on the shaft, a plurality of oscillating and rotary gummers mounted on the frame and positioned above the shaft, brackets carried by the frame, laterally adjustable bearings carried by the brackets, a saw mandrel carried by the bearings, as and for the purpose specified.

5. In a grinding and gumming machine, 60 a frame, a shaft carried by the frame, a plurality of grinding wheels keyed to the shaft, a plurality of rotary and oscillating gummers carried by the frame and positioned above the grinding means, adjustable bearings carried by the frame, a saw

mandrel carried by the bearings, a plurality of saws mounted on the mandrel, a drive shaft, means operatively connecting the drive shaft to the first-mentioned shaft, means operatively connecting the gummers 70 to the drive shaft, and means for automatically stopping the operation of the grinders and gummers upon one revolution of the saw mandrel.

6. A gumming and grinding machine including a frame, a shaft rotatably carried by the frame, a plurality of grinding wheels keyed to the shaft, bearings carried by the frame, means for adjusting the bearings laterally and longitudinally of the frame, 75 a saw mandrel carried by the bearings, a plurality of saws keyed to the mandrel, means for rotating the mandrel step by step, a plurality of rotary and oscillating gummers mounted above the grinders, a drive shaft, means operatively connecting the drive shaft with the grinding shaft, and means operatively connecting the gummers 80 with the drive shaft.

7. In a gumming machine, a saw mandrel 90 support, a mandrel mounted in the support, a swinging frame, means for swinging the frame, a plurality of vertical shafts carried by the frame, gummers keyed to the shaft, and means for rotating the shaft.

8. In a gumming and grinding machine, a frame, an adjustable mandrel support, a mandrel carried by the support, a plurality of saws keyed to the mandrel, a swinging frame carried by the first-mentioned frame, a drive shaft carried by the first-mentioned frame, a driven shaft carried by the first-mentioned frame, grinding wheels carried by the driven shaft, means operatively connecting the drive and driven shafts, a plurality of vertical shafts carried by the swinging frame, gummers mounted upon the vertical shafts, a shaft carried by the swinging frame, means operatively connecting the last-mentioned shaft to the vertical 100 shafts, means operatively connecting the driving shaft with the shaft carried by the swinging frame, a plurality of eccentrics carried by the driven shaft, and means operatively connecting the eccentrics with the 105 swinging frame, as and for the purpose specified.

9. In a gumming machine, a frame, an adjustable mandrel support carried by the frame, a mandrel mounted in the support, a plurality of saws carried by the mandrel, a ratchet wheel detachably secured to the mandrel, a swinging block carried by the frame, a plurality of vertical shafts carried by the frame, a plurality of gummers keyed to the 110 shafts, a longitudinally extending shaft carried by the block, means operatively connecting the vertical shaft with the longitudinally extending shafts, a driving shaft, a driven shaft, means operatively connecting 115 the driving shaft with the driven shaft, a plurality of eccentrics carried by the driven shaft, and means operatively connecting the eccentrics with the 120 swinging frame.

the driving shaft with the driven shaft, a plurality of cams carried by the driven shaft, means operatively connecting certain of the cams with the swinging frame, an arm operated by one of the cams, a dog carried by the arm for engaging the ratchet wheel, as and for the purpose specified.

10. A grinding and gumming machine, a frame, an adjustable saw mandrel support carried by the frame, a mandrel mounted in the support, a plurality of saws secured to the mandrel, a ratchet wheel detachably secured to the mandrel, a grinding shaft rotatably carried by the frame, a plurality of 15 grinding wheels secured to the shaft, a swinging block carried by the frame, a plurality of vertical shafts rotatably carried by the block, a longitudinally extending shaft carried by the block, means operatively connecting the vertical and longitudinal shafts, 20 gummers keyed to the shafts, a driving shaft, a driven shaft, means operatively connecting the driving shaft with the driven shaft, means operatively connecting the 25 driving shaft with the longitudinal extending shaft, means operatively connecting the grinding shaft with the driven shaft, means operatively connecting the driven shaft with the block, means operatively connecting the 30 driven shaft with the ratchet wheel, as and for the purpose specified.

11. A grinding and gumming machine, a frame, an adjustable saw mandrel support carried by the frame, a mandrel mounted in the support, a plurality of saws secured to the mandrel, a ratchet wheel detachably secured to the mandrel, a grinding shaft, a plurality of grinding wheels keyed to the shaft, a drive pulley and an idle pulley car-

ried by the shaft, a swinging frame, a plurality of rotary gummers carried by the frame, a driving shaft, a driven shaft, means operatively connecting the driving shaft with the driven shaft, means operatively connecting the driving shaft with the 40 gummers, a belt connecting the driving shaft with the idle and drive pulleys, idle and drive pulleys secured to the driving shaft, a shift rod mounted longitudinally of the frame, a belt shift carried by 45 the rod and engaging the belt, a contractile coil spring normally tending to shift the rod, a sliding rod, the meeting ends of the rods having hooked ends, an arm carried by the ratchet wheel and arranged to engage 50 the sliding rod to move the first-mentioned shift rod to disengage the same from the hooked end of the second-named rod, a pivoted lever operatively connected to the second-mentioned rod, an arm, a shoulder 55 formed on the arm arranged to engage the pivoted lever, an expansion coil spring engaging the lever and normally tending to swing the same on its pivot, a second arm carried by the ratchet wheel and arranged to 60 engage the pivoted lever to lift the same out of engagement with the shoulder, a belt shift carried by the inner end of the lever, a belt trained around the pulleys carried by the drive shaft, and the last-mentioned belt 65 shift engaging the second-mentioned belt, as and for the purpose specified.

In testimony whereof I affix my signature in presence of two witnesses.

GEORGE PIERCE NABORS.

Witnesses:

H. D. PERKINS,
FRED WOODALL.
